UNITED STATES PATENT OFFICE.

BERTHA M. BEHL, OF ROCHESTER, ILLINOIS.

CURTAIN-SUPPORT.

1,216,271.

Specification of Letters Patent.

Patented Feb. 20, 1917.

Application filed August 11, 1915. Serial No. 44,983.

To all whom it may concern:

Be it known that I, BERTHA M. BEHL, a citizen of the United States, residing at Rochester, in the county of Sangamon, State 5 of Illinois, have invented certain new and useful Improvements in Curtain-Supports; and I do hereby declare the following to be a full, clear, and exact description of the invention, such as will enable others skilled in 10 the art to which it appertains to make and use the same.

This invention relates to new and useful improvements in curtain poles and supporting means therefor, and is particularly directed to the provision of such a device which is adapted to be used in connection 15 with the usual roller shades.

It is the object of the present invention to provide a curtain supporting device whereby 20 the curtain may be so mounted that it is held outwardly of the plane of the shade to prevent binding thereof and whereby at the same time the upper edge of the curtain is positioned adjacent the window frame to 25 avoid the usual unsightly appearance incident to suspending the top edge of the curtain from a line outwardly of the roller.

It is further an object of the invention to provide such a device including novel means 30 for holding the curtains drawn apart in any desired position.

It is further the object to provide such a curtain support which is attachable to the edge portions of a window frame whereby 35 marring of the face of the frame upon attachment of the device is obviated.

With the above and other objects and advantages in view, the invention resides more particularly in the novel combination, formation and arrangement of parts as more 40 fully described hereinafter and pointed out in the appended claims.

Reference is had to the accompanying drawings, wherein similar characters of 45 reference designate corresponding parts throughout the several views, and in which:

Figure 1 is a front elevation of a window showing the improved curtain pole and supporting means attached thereto.

Fig. 2 is a perspective view of one end portion of the double pole member.

Fig. 3 is a sectional view on the line 3—3 of Fig. 2.

Fig. 4 is an end view of the device.

Referring now more particularly to the accompanying drawings, the member for

supporting the curtain comprises a pair of rods 5 and 6, each of which is formed of telescoping tubular sections to adapt the device for use with various widths of windows. These rods are held in spaced parallel relation by end plates 7 provided with openings 8 receiving the rods, wherein they are secured as by soldering. For supporting these rods at the top of a window a cylindrical plug 9 is threaded into the ends of each rod and the intermediate portion of the plug has its sides cut away at 10 to form an oblong cross section adapted to engage in brackets hereinafter to be described. Outwardly of these portions 10 the plugs are threaded for the reception thereon of ornamental knobs 11. The brackets 12 for supporting the rods are flat in shape and adapted to be secured at their inner ends to the 75 edge portions of the window frame. The brackets extend outwardly of the frame at a downward inclination and are provided each with a pair of spaced slots 13 opening at the top edges of said brackets to receive 80 the respective cutaway portions 10 of the plugs 9 secured in the ends of the rods. Thus the rods may be readily attached to or removed from the brackets, and the brackets may be thus detached and removed without 85 marring the front face of the window frame.

It is observed that by the inclination of the brackets the rod 6 is disposed outwardly of and below the rod 5 so that a curtain 90 may be secured on the rod 5 and extend over the rod 6 whereby it is held spaced outwardly of a shade that may be desired to be placed on the window and not bind the same.

The curtain would preferably comprise 95 two sections slidably mounted on the rod 5, and to hold said sections of the curtain drawn apart to any desired degree, each of the sections of the rod 6 is provided with a longitudinal series of V-shaped incisions 100 and the material embraced by these incisions is adapted to be bent outwardly to form prongs 14 for holding the curtain.

A comparatively simple structure has thus been provided which is capable of 105 manufacture at a comparatively low cost and which will nevertheless efficiently perform the various functions set forth.

While I have illustrated and described a particular embodiment of my invention, I 110 have merely done so for the sake of convenience and I do not wish to be limited to

that particular embodiment as it is obvious that numerous changes may be made within the details of construction thereof without in any way departing from the spirit of the invention as claimed.

What I claim is:

1. A curtain support including a member arranged when in one position to permit sliding of a curtain thereon and when in a second position to prevent sliding adjustment of said curtain, and means to hold said member in either of said positions.
2. A curtain support having reversible curtain supporting faces, one face permitting the ready slipping and adjustment of the curtain, the other face being provided with curtain engaging devices arranged to hold the curtain permanently in proper adjustment, and brackets supporting said curtain support in positions to bring said faces selectively into engagement with a curtain.
3. A duplicate curtain pole consisting of a pair of permanently spaced and portable rods, and means to hold said rods in rigid

spaced relation, one of said rods being 25 smooth for slidable movement of the curtain therealong and the other rod being roughened to prevent sliding movement of the curtain therealong.

4. A curtain support comprising a pair of 30 rods held in spaced relation, one being smooth to permit of the ready adjustment of a curtain thereon, the other having means to engage and hold the curtain when supported thereon, and brackets for the rods providing means for the support of the rods to permit of the adjustment of the curtain on the smooth rod and for the reversal of said rods to bring the rod provided with curtain engaging means into position to 35 support the curtain.

In testimony whereof, I affix my signature, in the presence of two witnesses.

BERTHA M. BEHL.
